United States Patent Office

Des. 184,100
Patented Dec. 16, 1958

184,100

PUFFED TEXTILE FABRIC

Douglas D. McCord, New York, N. Y., assignor to Chicopee Mills, Inc., a corporation of New York

Application September 27, 1957, Serial No. 47,893

Term of patent 14 years

(Cl. D92—1)

Fig. 1 is a plan view of a puffed textile fabric showing my new design;

Fig. 2 is a side edge view; and

Fig. 3 is an end edge view.

I claim:

The ornamental design for a puffed textile fabric, as shown.
